UNITED STATES PATENT OFFICE.

ROBERT W. VAIL, OF NEW YORK, N. Y.

BURGLAR-ALARM SYSTEM.

1,374,255.

Specification of Letters Patent. Patented Apr. 12, 1921.

Application filed July 11, 1917. Serial No. 179,864.

To all whom it may concern:

Be it known that I, ROBERT W. VAIL, a citizen of the United States, residing at New York, in the county of New York and State of New York, have invented new and useful Improvements in Burglar-Alarm Systems, of which the following is a specification.

The object of my invention is to provide certain improvements upon the burglar alarm system disclosed in my Patent No. 1,238,363 of August 28, 1917, of which this is in part a continuation, and which relates to the protection of banks, residences, vaults, etc., against robbery, and which is also designed to prevent the escape of convicts through windows, walls or doors of prisons, and which is arranged to sound an alarm whenever the system is tampered with in any way, or an attempt to escape past windows or doors protected by the system is made.

It is an especial object of my invention to provide a novel plate having a series of channels through which an endless traveling element passes; to arrange such channels through hinges of doors or shutters; to provide bars having similar channels; to provide other elements, such as bent plates, pulleys and screws etc., with orifices through which an endless cable may travel to increase the security of the burglar alarm system, without interfering with the functions of the various members through which it travels.

It is further my object to coordinate such an alarm system with clocks which may be adjusted to prevent the sounding of the alarm at predetermined times.

It is further my object to diversify the arrangement of endless chains and endless cables and to arrange them in a connected series, that is, with two or more individual endless chains or cables operatively connected together, one of the endless chains or cables not being directly connected with the propelling apparatus, but caused to be actuated by the action of the first endless element and a connecting medium to permit of a more diversified arrangement of the burglar alarm system, and to make it impossible to tamper with it without sounding the alarm.

It is further my object to provide a novel arrangement of chains as a part of the burglar alarm system. It is also my object to

use a series of individual endless elements 55 in order to permit of the easy repair of the chain system in series in case of breakage.

It is also my object to provide an improved arrangement of individual endless 60 chains in series in order that the chains when worn may be readily replaced and may be readily assembled.

It is also my object to provide a novel hollow axle in conjunction with grooved and 65 chain wheels over which pass the protective endless cords and chains; the endless elements operating through the hollow axles whereby the burglar alarm system may be more effectively applied to doors or hinged 70 windows or to any form of protective plate of this system, and which arrangement will render it impossible to remove the said grooved and chain wheels and a door or window without sounding the burglar alarm. 75

It is further my object to provide a burglar alarm system having a series of individual endless elements instead of one continuous endless element running through the entire protective system and to make impossible 80 successful tampering with such a burglar alarm system by guiding the endless traveling elements through the hollow axles of gears, chain wheels, or grooved wheels forming a part of the apparatus. 85

It is also my object to provide novel arrangements of protective plates of any suitable material in connection with the alarm system, the endless traveling element (or elements) being guided through apertures 90 extending through such plate or plates, which may be of steel, glass or other material.

It is also my object to provide bolts and screws having openings to permit the endless traveling element to pass through such screws or bolts, to make impossible any unauthorized attempt to remove them without sounding the alarm. 95

It is also my object to provide novel "locking boxes" in elongated form which may be cast as part of the protective plate and be attached to walls or other supports to make them immovable without sounding the alarm when the endless element is passing through 100 them and in operation.

It is further my object to use such "locking boxes" to support a guide wheel within

the compartment to guide the endless traveling element.

It is also my object to provide a protective plate made or arranged in sections which 5 may be used collectively or individually and in correlation with the casements set forth in my Patent No. 1,238,363.

Further, my object is to provide a novel 10 pronged device arranged adjacent to the endless traveling chain to cause its stoppage in the event of any slack occurring in it, as a result of tampering with the apparatus.

It is further my object to provide novel 15 time regulating apparatus for controlling, stopping, or starting the operation of the system at predetermined hours.

It is further my object to provide novel 20 combination and arrangement of parts as will hereinafter be fully set forth with the accompanying drawings illustrating the invention, in which:

Figure 1 is a vertical section through one form of protective plate in combination with my endless traveling element;

25 Fig. 2 is a vertical cross section of another form of protective plate having a series of apertures and through which are operated both endless chains and endless cables;

Fig. 31^B is a diagrammatic representation of mechanical controlling means for the bell 65^P shown in Fig. 31;

Fig. 32 is a detail of a modified timing means whereby the whole system may be rendered inoperative at a predetermined time;

Fig. 33 is a detail of a vertical slidable switch-block shown in Fig. 32;

Fig. 34 is a diagram, partly in section and partly in elevation, of the system arranged to protect a door;

Fig. 35 is an enlarged fragmentary elevation, partly in section of a combined endless chain and endless cable protective arrangement;

Fig. 36 is a section on line 36-36 of Fig. 35;

Fig. 37 is a view of the governor mecha-

nism, partly in elevation and partly in section in combination with an endless chain system, shown in diagram;

Fig. 38 is a view of a modified form of alarm;

Fig. 39 is an enlarged rear view of door 74 in connection with means for detaching the door-protective cable;

Fig. 40 is a view of a vault protected by my system, its wall being shown partly in section;

Fig. 41 is a horizontal section through a vault protected by both endless cables and endless chains;

Fig. 42 is a section on line 42-42 of Fig. 43;

Fig. 43 is an elevation partly in section of a vault compartment protected by my alarm system;

Fig. 44 is a section through the floor or ceiling of the vault;

Fig. 45 is a detail of a modified form of supporting means for the rollers or pulleys;

Fig. 46 is a section showing the castings and fastenings used in the vault;

Fig. 47 is a front elevation partly in section of a system arranged to protect a vault;

Fig. 48 is a section partly in diagram of the system employing a novel entanglement box for stopping the chain when slack occurs in it as a result of tampering;

Fig. 49 is a detailed end view of the entanglement box;

Fig. 50 is a section on line 50-50 of Fig. 51;

Fig. 51 is a front elevation of the entanglement box;

Fig. 52 is a front elevation of the alarm system applied to a window in combination with the device for providing slack cable to permit an authorized person to open the window;

Fig. 53 is a horizontal section on line 53-53 of Fig. 52;

Fig. 54 is a horizontal section on line 54-54 of Fig. 52;

Fig. 55 is a diagrammatic illustration of the invention arranged to protect a series of windows;

Fig. 56 is a front elevation of my compensating device;

Fig. 57 is a vertical section of Fig. 56;

Fig. 58 is a horizontal section on line 58-58 of Fig. 56;

Fig. 59 is a horizontal section on line 59-59 of Fig. 56;

Fig. 60 is a view partly in elevation and partly in section on line 56-56 of Fig. 61;

Fig. 61 is a detailed elevation of the slotted adjusting device;

Fig. 62 is a modified form of protective plate in combination with pulley supporting casements;

Fig. 63 is a section on line 63-63 of Fig. 62;

Fig. 64 is a diagrammatic view shown in section and in elevation of my invention applied to a building.

Like characters of reference designate like parts throughout the various views.

Referring to the accompanying drawings I provide an endless traveling element 1 and pulleys 2 supported by axles 3. To increase the usefulness of my alarm system I may provide a plate 4 of any suitable material such as glass or metal through which the endless traveling element may travel in longitudinal channels 5 disposed preferably in parallel arrangement as shown in Fig. 1. Plate 4 has a cut away portion or pocket 6 at each end in which the pulleys 2 are mounted as shown in Fig. 1.

In Fig. 2 there is illustrated a top plate or casement cover 7 having a concealed finger 10 which serves as a securing member. The plate is secured to the body of the casement by screw 11. In addition to the rollers 2 I may also provide sprocket wheels 9 so that both endless chains and endless cables may be used in the system or in any modification of it.

In Figs. 3 and 4 a modified form of plate is shown having side pockets 12 and horizontal channels 13 in addition to the vertical channels 5.

Fig. 5 illustrates a modified window plate member 16 preferably in one casting having longitudinally disposed channels 5 for the endless cables 1. Casements 17 are of U-shape and are provided with covers 15. In this figure are illustrated small rollers 18 mounted within casement 17 as illustrated. Pulleys 19, shown in dotted lines, are for a secondary protective endless traveling member 1.

In Fig. 6 there is illustrated a front plate or cover 21 for a window. I may provide apertures 20 of any suitable shape in this cover member to facilitate the assembling and adjustment of the cable especially in connection with the apertured screw 22. These apertures 20 may be of any suitable size so as to admit a tool, or if desired, the hand. Lateral pairs of perforations 20' are provided for the attachment of any form of hinges if protective plate is used as a protective shutter.

In Fig. 7 a modified form of protective window construction is shown, comprising the channeled glass plate 24, and the channeled U-shaped plate 25 which is secured to plate 26 by a concealed screw. In Fig. 8 the method of utilizing screws 22 is illustrated, the screws extending into the wall 27. The endless cable may be inserted through the aperture 23 in the screw 22 by utilizing aperture 20 or by first threading

the cable through the screw and coiling it about the screw a sufficient number of times so that it will unwind as desired as the screw is put in place.

5 In Fig. 10 there is illustrated a novel means of protecting a window by my system by utilizing bars 28 having apertures 29 through which the endless cable 1 travels. Bars 28 are secured to the window 10 sash or frame by means of fillets 31. The U-shaped form of the frame 30 is illustrated in Fig. 11.

15 Fig. 12 illustrates a modified form of protective bar having a longitudinal channel 33 for the endless cable 1 and a plurality of transverse channels 29 to accommodate the endless traveling elements moving in directions at right angles to each other. Fig. 13 shows in cross section the disposition 20 of member 31.

25 In Fig. 14 is illustrated a separable locking box 34 adapted to afford increased protection against tampering with the cables and having a novel arrangement of pulleys 2 and 18 as illustrated. Locking box 34 is secured by suitable screws 36 or similar fastening means. Hidden from view by the locking box are concealed screws 35. It is within the contemplation of my invention 30 to provide these screws with longitudinal channels and to carry the endless cable through them if desired.

35 In Figs. 15, 16, 17, and 18 is illustrated the locking block 37 within which the combining locking block 39 is positioned both of these blocks being provided with suitable channels for the endless traveling element or elements. An endless chain 38 mounted on a sprocket wheel 9 may constitute one of 40 the endless traveling elements.

45 In Fig. 19 is illustrated a novel apertured pulley 41 arranged to permit a secondary cable 1^a to pass through the aperture in the pulley while the primary cable 1 travels over its periphery.

Fig. 20 illustrates method of mounting pulleys 41 and 18 and the arrangement of the traveling element 1^a.

50 In Fig. 21 there is illustrated a vertical strut 42 which serves as a mounting means for bars 32.

55 In Figs. 22, 23, and 24 is illustrated an elongated locking box 43 from which the endless cable 1 travels through the horizontal channel 44. The elongated locking box is preferably held in place by the concealed screws 35 as shown in Fig. 24.

60 In Fig. 25 is illustrated a clock and an alarm disengaging mechanism comprising clock 45, ratchet 46, pawl 47 and sheave 48 to which is attached the stationary cable 49.

Fig. 26 is a front elevation of clock 45 which may be of any suitable variety. Attached to clock 45 as shown in Fig. 26 is an 65 auxiliary taut cable 73.

Fig. 27 illustrates in detail the novel rotatable disk 50 which is provided with apertures 52 and which is normally held in the position shown by means of spring 127 to permit of the completing of an electric circuit and the sounding of an alarm when the governor weight drops as a result of an interruption of the usual operation of the traveling cable.

70 Disk 50 is rotatably mounted on the stationary disk 51. Attached to the rotatable disk 50 is a line 72, secured to the taut cable 49, which in turn is connected with a clock 45. Line 72 is guided over roller 130 as shown in Figs. 27 and 30.

75 In Fig. 28 the function of rotatable insulated disk 50 is clearly shown. When the governor weights 64, shown in Fig. 31, lower the pivot arms 59, revoluble governor disk 60 to which they are attached and the vertical movable plate 57 are lowered by arms 58, and guided in grooves 54, by governor frame 55 the contact points 128 carried by plate 57 will pass through the apertures 52 in the insulated disk 50 to make the electric 80 contact in the usual way with corresponding contact posts 56. But when disk 50 is rotated by clock 45 the alarm mechanism of which is set for any predetermined time so as to close the apertures 129 in the stationary disk 51, the electric contact points 128 are prevented from making contact with contact posts 56 and the alarm is prevented from sounding until the disk 50 is released and allowed to rotate to its normal 85 position by the release of tension on cable 49 by clock 45. 61 designates the central guide post of the governor frame. Fig. 30 is a side elevational view of the mechanism shown in Fig. 28.

90 In Fig. 29 I have illustrated diagrammatically a suitable switch 62 arranged to engage the stationary cable 49 and also a spring 63 which may be employed to cause the cable 49 to return to its normal position 100 when released by switch 62.

105 In Fig. 29 discloses an automatic clock device connected with electric motor 62 to stop motor by disconnecting the current at any predetermined time when the alarm clock 110 mechanism (of ordinary type) is set to turn winding wheel 48 (see Fig. 25) causing lever α of switch 62 to be drawn toward clock 45 to stop motor and simultaneously stopping the travel of the endless element 1. 115 The switch arrangement in Fig. 29 is designed primarily to automatically function in an unpeopled locked office or safety vault; the clock action which stops motor occurring say five minutes before the office is habitually opened in the morning. At the time the office is locked for the night the endless system 1 is not of course operating in an office which has been peopled during the day. When the office door is closed and locked the 120 125 130

motor (see 62, Figs. 29 and 31) is turned on by a movement of the lever α (Fig. 29) in the opposite direction than as noted above, that is in the direction of arrow z , and the 5 normal movement of endless element 1 commences and continues until automatically stopped at any predetermined hour in the morning, as above described. When the office door is closed and locked for the night, 10 the switch string 49 (Fig. 29) in grooves of guide rollers 4000, suitably affixed to walls or other support passes from the office room or rooms to hall box 97 (see Fig. 39), when the cable 49 can be reached to be pulled by 15 hand, causing the movement of motor lever α in direction of arrow z , thereby turning on the electric current and causing motor to operate and simultaneously starting the travel of endless element 1, which action 20 continues during the night and until the motor is automatically stopped in the morning, as above described.

Fig. 31 is a diagrammatic view of an arrangement of governors in series, the first 25 of the governing mechanisms being designated as A; the second as B, and the third in the series as C. In connection with this series arrangement of governors I provide stationary cable 49 mounted on rollers 48 and secured by spring 63 to fastening D. Lines 72^v operatively connect the several governor mechanisms with stationary cable 49 which in turn is connected with a clock 45. Clock 45 is connected by auxiliary 30 stationary cable 73 with removable pin 66. Pin 66 is releasably inserted through block 67 into the vertically slidable plate 69. As shown in Fig. 33, plate 69 is an intermediate 35 plate provided with apertures 68 which permit of longitudinal sliding movement of plate 69 when pin 66 is withdrawn. The dropping or lowering of plate 69 gives slack to cable 72 and thus to member 84 and endless cable 1, thereby obviating the sounding 40 of the alarm bell 65^P, at the time of opening in the morning the office or building in which the system is installed, when the normal operation of the alarm by the opening 45 of the door by the proprietor or employee of the door by the proprietor or employee 50 would be a source of annoyance. The weight of plate 67 is such that it does not act to sound alarm 65^P.

Bell 65^P corresponds in function with bell 118 of applicant's Patent No. 1,238,363, and 55 may be either a conventional mechanical bell (as shown in Fig. 31^B) or a conventional electric bell (as shown in Fig. 31^A). Alarm bell 65^w, 65^x, 65^y, and 65^z are conventional electric bells, as in applicant's Patent No. 60 1,238,363, and are suitably wired to battery 71, and are sounded when any of the parallel strands of the traveling element 1 are tampered with or pushed out of their line 65 or normal direction of travel.

Referring to Fig. 31, 31^A, and 31^B, cable

72 is attached to a gong-sounding member 600, which either releases a mechanically sounded alarm bell, as in Fig. 31^B, or closes the circuit of a conventional electric alarm bell, as in Fig. 31^A. Any suitable electrical 70 or mechanical gong may be utilized. Alarm bell 65^x, 65^y, 65^z, and 65^w are the ordinary conventional type of electric bell or gong, and the complete circuits are disclosed in Fig. 31 of the drawings.

Fig. 32 is an enlarged view of members 66, 67, 69. Fig. 33 is a detail view of member 69 which is provided with slots 70 through which guiding pins 68 project, to engage in switch block 67.

In Fig. 34, door 74 which is protected by my alarm mechanism, is provided with a novel channeled hinge 75, through which cable 1 travels, thus rendering it impossible to remove the door without sounding the 85 alarm.

Fig. 35 illustrates means for operating a combined endless cable and endless chain as a protective device for a window or a wall. I provide suitable adjustable frames for supporting rollers 2 and sprocket wheels 9. I also provide a hollow axle 79 for roller 2 and sprocket wheel 9. This axle affords a passage for auxiliary cable 1^a, thus rendering it impossible to alter the mechanism without sounding the alarm.

To facilitate adjustment of frame 76 I provide slots arranged in the form of a cross to permit of adjustment either longitudinally or laterally.

Fig. 36 illustrates beveled gears 131 and their arrangement for operating chain 38 so as to protect a door or window.

Fig. 37 illustrates a means for connecting the endless chain 38 with the spindle 61 105 of governor frame 55, consisting of a combined sprocket wheel and gear 80 meshing with pinion 81, which latter member is carried by post or spindle 61. The sprocket teeth of member 80 mesh with chain 38, the 110 gear 80 being driven by the endless chain.

Fig. 38 illustrates a governor operated alarm including a visible alarm and a detonating alarm device.

The detonating alarm consists of a percussion cap 87 mounted in the barrel 88, the percussion cap being detonated by spring actuated hammer 86 which is released by trigger 85 when the extended arm 84 carried by the vertically movable member 57 of the governor is lowered following an interference with the endless traveling element which normally results from any tampering with the system. The governor weights 64 are pivotally attached to the stationary plate 125 120 by arms 124. Weights 64 are also pivotally connected with the vertically movable member 57 by the arms 59.

The visible alarm device is operated by means of an insulated member 83 carried by 130

a vertically movable governor plate 57. Member 83 is adapted to make or break the electric circuit between one of the electric contact members 89. The electric lamp circuit includes a battery 94, electric conductors 132, a motor 90 arranged to rotate lamp standard 95 which carries the revolving electric lamp 91. A contact brush 93 electrically connects wire 132 with the middle 10 socket of lamp 91 to complete the electric circuit. Lamp 91 is provided with a darkened or reflector portion 92, whereby an intermittently flashing light is obtained which cannot fail to attract attention when the 15 alarm is operated. Member 80 may operatively engage cable 1, as illustrated, as well as chain 38. Cable 1 may be operatively connected to compensating weights 82.

Fig. 39 which is an enlarged and reversed 20 view of door 74 illustrates means for providing slack to enable authorized persons to enter without sounding the alarm. This result is attained by giving slack to cables 96 which are normally secured by rings to suitable 25 hooks 99, this mechanism being contained within a suitable case 97, which may be locked when desired.

Figs. 40, 41, 42, 43, 44, 45, and 46, illustrate details of a vault to which my protective alarm system is applied. Fig. 40 shows 30 one means of mounting rollers 2. Fig. 45 illustrates another method of mounting rollers 2, by means of bars 126. Fig. 41 illustrates means for mounting the casements which contain the rollers and sprocket 35 wheels for the endless traveling elements.

The protective plates of vault are provided with flanges 100, which are suitably fixed to central vault frames 101. Figs. 42 40 and 43 illustrate a protected compartment of the vault. Fig. 44 shows a modified form of vault wall. Fig. 46 illustrates the square-shaped supports 101 which are fastened to 45 projections 100 of vault walls 103, this being my preferred form of vault construction. Fig. 47 shows the front plate of the vault and the disposition of the traveling element. Fig. 48 illustrates an entanglement box 104 having inwardly projecting prongs 50 adapted to engage and stop the traveling element in the event that there is slack as the result of tampering or interfering with its usual operation. This entanglement box 104 is especially designed for use where an endless chain is employed as the traveling element.

Figs. 49, 50 and 51 illustrate the entanglement box in detail.

In Fig. 52 are illustrated window sashes 60 106 mounted in main sash frame 107. The glass panes 111 are provided with channels 112 for the traveling element 1. 108 designates a reciprocable slack giving pulley which is operatively connected to the knob 65 110, which is slidably mounted in the slot-

ted bar 109. This device is for the purpose of giving slack to enable authorized persons to open the window without sounding the alarm.

Fig. 53 is a section through one of the 70 panes showing the disposition of the traveling elements. Fig. 54 is a section on line 54-54 of Fig. 52 and illustrates the means for inserting and securing the window frames in place. 114 designates the bottom 75 bar which locks the main frame in place, bar 114 being secured by locking pin 113. Fig. 55 shows a means for mounting an endless traveling cable or endless traveling chain to protect a series of windows. Figs. 80 56, 57, 58, 59 illustrate operating weights 115 to which are mounted pulleys 2 for the endless cable 1. In the guiding frame 121 is mounted an actuated bar 116 having inclined projections or lugs 117 positioned to 85 engage corresponding lugs 118 carried by weight 115. A spring 119 bears against head 120 of bar 116 to cause it to move outwardly and disengage lugs 117 from lugs 118, at a predetermined time as controlled 90 by clock 45.

In the arrangement of the compensating device illustrated in these figures a single endless element passes through the compensating device twice over the pulleys 2. 95 When a door is opened the weights 115 are lifted simultaneously. Members 115 are of a sufficient weight so that the tension of the endless element will not raise them in consequence of the ordinary fluctuation of the 100 ordinary motor action.

Figs. 56, 57, 58 and 59 relate to the adjustment of burglar alarm parts to operative position after the office door is closed and locked for the night. Rod 116 (Figs. 105 56, 59) locks weights 115 in operative position after the upper rod (Figs. 56, 58) has been moved in the required direction, allowing weights 115 to drop to locked position beneath the projection of rod 116. The 110 upper rod is thus moved by pulling attached string *c*, *c* being guided to hall box (Fig. 39) from room through apertures and into box 97 where it can be reached at any time and after office door or vault or dwelling 115 house door is closed and locked. (See Fig. 34.) Weights 115 rise when door is opened and during the day would be pinned in a fixed elevated position to remain immovable during the opening and closing of door. 120 The slack of element 1 or the movability of weights 115 permits the ordinary opening of door during business hours, without braking the element 1. Before and after the office door is closed and locked for the 125 night weights 115 are supported in unlocked position—unlocked in the sense that weights 115 can be raised by the reopening of the door before string *c* is pulled. They are dropped to locked position (in the sense 130

that weights 115 cannot be raised upon re-opening the door) by drawing the string *c* at box 97 (Fig. 39). The alarm mechanism of attached clock set for and operating at a predetermined time (a given hour in the morning) revolves the winding wheel 48, winding the string 49 around 48 and drawing rod 116 toward clock 45 and drawing the projection of 116 from above projection 10 of 115 so that members 115 are unlocked and rise unimpeded, when the office, vault or other door is ordinarily opened a moment or so after the said predetermined time in the morning. In the case of a burglar attempting to open a door protected by this apparatus, the endless traveling element 1 would be broken and the alarm sounded. The weights 115 with their correlative apparatus are intimately associated with the sounding of the alarms through the operation of the endless element and alarm mechanism. Weights 115 in locked position refuse slack to element 1, so that when the door is opened by the burglar element 1 is broken, the governors are affected and the alarms duly sounded.

Figs. 60 and 61 show the method of adjusting members 76 and 78, by means of bolt 122 which engages in the slots 77. Figs. 30 62 and 63 show novel casement members 123 mounted in a protective glass plate 111, members 123 containing the pulleys 2 as shown.

Fig. 64 illustrates various modifications of the protective apparatus applied to a building.

The operation of the invention has been set forth in connection with the foregoing description of the construction disclosed in the views described. The cable 1 is continuously traveling and as it is taut, any stretching or movement out of its regular path will exert such tension on the alarm mechanism as to reduce the speed of the governor, close the switch, and thus sound the alarm in consequence of the closing of the switch. It is within the contemplation of my invention to provide either a cable, a chain or a wire as the continuously traveling element, and the words "traveling element" when used in the claims are to be construed as referring to any of the foregoing members. It is also within the contemplation of my invention to provide any suitable form of incasing mechanism for the endless traveling element. The drawings illustrate my preferred form. It is further within the contemplation of my invention to provide any suitable form of grooved roller or wheel for mounting and supporting the cables or chains, and the word "roller" as used in the claims shall be construed as applying to any suitable rotatable element adapted to support the "traveling element".

65 I may provide suitable weights 115 in con-

nection with the propelling mechanism to compensate for the weight of an unusually long traveling element, and similarly to compensate for the diminished weight by its subtraction if an extra short traveling element is employed, thus keeping the endless traveling element taut throughout its length. Any separation or movement of the parallel lengths of the endless cable at any angle to their line of travel in even a slight degree 75 will sufficiently retard the governor as to cause the alarm to be sounded.

The words "securing element" when used in the claims are to be construed as referring to any hinge, bolt, screw, bar, block, plate, or the like used as a fastening or protecting member and having a channel for the passage of the endless traveling element.

The terms "locking box" and "locking block" are to be applied to the device hereinbefore illustrated and described by these names.

It is to be understood that I may modify the invention by arranging any of the mechanisms described in series instead of using them singly, and that it is within the contemplation of my invention to modify the shape, position, and number of parts used for or in connection with an opening or other portion of a structure to be protected, as I may elect.

It is also to be understood that it is within the contemplation of my invention to combine the use of an endless chain with an endless cable to increase the difficulties of 100 successful tampering with the system.

The words "protective plate" as used in the claims are to be construed as applying to a plate of any material, whether glass, metal or otherwise, and to a plate of any desired shape used for protective purposes in connection with an endless traveling element. The term "protective member" is to be construed as applied to walls, plates, bars, rods and pipes.

110 What I claim is:

1. In a burglar alarm system, the combination of an endless traveling element and a securing member having a channel through which the endless traveling element passes.

2. In a burglar alarm system the combination of one or more protective plates arranged to protect a given portion of a structure, the plates having channels, and endless traveling elements passing through the 120 aforesaid channels.

3. In a burglar alarm system the combination of a protective member arranged to protect a portion of a structure and having transversely disposed channels and one or 125 more traveling elements passing through the aforesaid channels.

4. In a burglar alarm system a protective device comprising a member supporting a locking block, a locking block member U-

130

shaped in cross section and positioned within the first named member, the members having aligned channels and one or more endless traveling elements passing through 5 the aforesaid channels.

5. In a burglar alarm system a protective device comprising a member supporting a locking block, a locking block member U-shaped in cross section and positioned with- 10 in the first named member, the members having aligned channels, one or more endless traveling elements passing through the aforesaid channels, and locking block fastening means.
15. 6. In a burglar alarm system an endless traveling element, pulleys over which the endless traveling element passes, and another set of pulleys having hollow axles through which a second endless traveling 20 element passes to prevent their displacement without sounding the alarm.

25. 7. In a burglar alarm system the combination of an endless chain, an audible alarm, a governor device, and means operatively connecting the governor device with the endless chain, said means comprising a combined gear and sprocket member, a sprocket member engaging the chain, a pinion en- 30 gaging the aforesaid gear, a rod to which the pinion is mounted and which is operatively engaged to the governor.

35. 8. In a burglar alarm a combination of endless chains and endless cables, pulleys and sprocket wheels supporting the aforesaid endless chains and endless cables and an adjustable frame to which the aforesaid pulleys and sprocket wheels are mounted.

40. 9. In a burglar alarm a combination of endless chains and endless cables, pulleys, and sprocket wheels supporting the aforesaid endless chains and endless cables and an adjustable frame to which the aforesaid pulleys and sprocket wheels are mounted, the frame being laterally and longitudinally 45 adjustable relative to the wall to which the frame is mounted and having a fastening member positioned within X-shaped slots to permit of adjustment described.

50. 10. In a burglar alarm system the combination of an endless traveling chain and one or more entanglement boxes having opposite inwardly turned prongs positioned in proximity to the chains, whereby the movement of the chain will be abruptly stopped by the prongs if the chain becomes slack in consequence of tampering.

55. 11. In a burglar alarm system the combi-

nation of one or more endless traveling ele- 60 ments arranged to sound an alarm if their movement is interrupted, a governor mecha- nism, and an audible alarm, the audible alarm being set in operation by the gov- ernor mechanism when the movement of the endless cable is interrupted.

65. 12. In a burglar alarm system the combi- nation of one or more endless traveling ele- 70 ments arranged to sound an alarm if their movement is interrupted, a governor device, and a visible alarm consisting of an electric lamp, the governor device being arranged to cause the lighting of the lamp when the movement of the endless traveling element is interrupted, and means for rotating the lamp to produce an intermittent flashing signal.

75. 13. In a burglar alarm system an endless traveling element, a plurality of slidable compensating weights operatively connected to the endless traveling elements, means for releasing said weights at a predetermined 80 time, and a clock operatively connected with said means.

85. 14. In a burglar alarm system the combi- nation with an endless traveling element adapted to sound an alarm, of a governor operated by the endless cable, means adapted to electrically connect the governor with the alarm upon interruption of the movement of the cable, and means for preventing such electrical connection to defer the sounding 90 of the alarm to a predetermined period, the last named means comprising a spring controlled insulating disk having orifices, and a clock to which the aforesaid rotatable disk is operatively connected and by which it is released at the desired time to permit of electrical connection between the governor device and the signal device being made through the orificed portions of the rotatable disk substantially as illustrated.

95. 15. In a burglar alarm system, an endless traveling element, alarm bells arranged to be sounded when the customary movement of the endless traveling element is interrupted, a clock, a stationary cable connected thereto, 100 an auxiliary stationary cable, said cable being connected to the clock and to the hereinafter described pin, a slidable plate, an alarm to which said slidable plate is attached, a pin removably engaging said slid- 110 able plate to prevent its movement and to thereby control the sounding of the alarm until released by the clock at a desired time.

ROBERT W. VAIL.
